United States Patent Office.

WILLIAM STANFIELD, OF FLORA, ILLINOIS.

Letters Patent No. 92,549, dated July 13, 1869.

IMPROVED SASH-BALANCE.

The Schedule referred to in these Letters Patent and making part of the same.

To all whom it may concern:

Be it known that I, WILLIAM STANFIELD, of Flora, in the county of Clay, and State of Illinois, have invented a new and useful Improvement in Window-Sash Supporters; and I do hereby declare that the following is a full, clear, and exact description thereof, which will enable others skilled in the art to make and use the same, reference being had to the accompanying drawing, forming part of this specification.

This invention relates to a new and improved method of supporting and operating the sashes of windows; and consists in substituting for the single-pulley wheel usually employed, two shafts, inserted horizontally in the upper part of the frame, and centrally of the same, which are each provided with a pulley within the frame, to which the inner and outer sashes are attached, by suitable cords, and with a pulley upon the outer side of the frame, to which the outside operating-cords are attached.

By this arrangement, the line of direction of the weight of the sash, and the power applied to the same, are in a direct line.

When the pulleys are arranged only upon the outside of the frame, as in the ordinary manner, and the operating-cords extend therefrom directly to the sashes, the latter are not raised in a direct line, but are caused to bind within the casing, which greatly retards their operation.

By arranging the pulleys and shafts as I propose, this difficulty is overcome, and the sashes raised and lowered with the utmost ease.

In the accompanying sheet of drawings—

Figure 1 represents a front elevation of a window with its sashes supported according to my invention.

Figure 2 is a vertical section of the same through the line *xx*.

Similar letters of reference indicate corresponding parts.

A is the window-frame or casing.

B is the window-sill.

C represents the lower sash.

D is the upper sash.

e e represent two horizontal shafts in the top part of the frame, one shaft for each sash. *e* is the shaft for the lower sash, and *e* is the shaft for the upper sash.

On the outer ends of these shafts are pulleys *ff*.

gg represent cords, which are attached to and wound around these pulleys, from whence they extend and pass around the small pulleys *g g*, on the front casing, and from thence down to the fastening-clamps *h h*, as seen in the drawing.

Upon the back portion of each of the shafts *e e* are other pulleys, directly over their respective sashes, marked *i*, one of which is seen in fig. 2.

J J represent cords, which are attached to these pulleys *i* and to the sashes, as seen in the drawing.

The operation will be readily understood from the drawing.

By pulling down on the cords *g*, the shafts *e e* will be revolved, which will of course revolve the pulleys *i*, wind up the cords *J*, and raise the sashes.

When either of the sashes is suspended by its cords, the upper one would be raised by revolving the shaft *e* and winding up the cord *J*, and be lowered by loosening its hand-cord *g* from the clamp *h*. The other sash is operated in the same manner, only the motions are reversed. The sashes are lowered by their own gravity, but raised by pulling down on the cords *g g*.

It will be seen that the clamps *h* grip the cords *g* in such a manner that any upward movement or strain only serves to tighten them.

They are loosened by pressing on the points *k k* of the clamps.

The clamps *h* are each composed of a lever, pivoted within a suitable keeper attached to the frame. The lower ends of these levers are inclined or bevelled, to correspond with the bevelled interior of the keeper, as shown in dotted lines, fig. 1, of the drawing, and their upper ends, *k*, extend without the keeper, as before mentioned.

The sashes (either of them) can thus be held in any desired position without the use of weights.

In fig. 2, *L* represents a bolt, by which the sashes are fastened together when they are closed.

Having thus described my invention,

I claim as new, and desire to secure by Letters Patent—

In raising windows, substituting for the single-pulley wheel the shafts *e e*, arranged as described, and furnished each with one pulley within the window-frame and one without the same, to which the sash-operating cords are attached, so as to allow the line of direction of the weight of the sash and the power applied thereto to be in a direct line, as herein shown and described for the purpose specified.

The above specification of my invention signed by me, this 24th day of February, 1869.

WILLIAM STANFIELD.
